UNITED STATES PATENT OFFICE.

NELSON B. COOPER, OF LIBERTY, INDIANA.

VEHICLE-SPRING.

SPECIFICATION forming part of Letters Patent No. 268,193, dated November 28, 1882.

Application filed June 22, 1882. (Model.)

To all whom it may concern:

Be it known that I, NELSON B. COOPER, of Liberty, in the county of Union, and in the State of Indiana, have invented certain new and useful Improvements in Vehicle-Springs; and I do hereby declare that the following is a full, clear, and exact description thereof, reference being had to the accompanying drawings, and to the letters of reference marked thereon, making a part of this specification.

This invention relates to certain improvements in vehicle-springs; and it has for its objects to provide a compound spring that will play more freely and uniformly than those in general use. These objects I attain by the means illustrated in the accompanying drawings, in which—

Figure 1 represents a longitudinal and Fig. 2 a transverse section of my invention.

The letter A indicates a bolster, to be attached to the axle of a vehicle, and B a transverse box or grooved beam, upon which the vehicle-body is to be supported. The bolster is hollowed out, as indicated, and on the inside is provided with vertical grooves C, located opposite each other, for the purpose hereinafter specified.

The letter D indicates two levers, recessed at E, and pivoted together by means of a fulcrum-pin, F, which projects at each end, and is adapted to play vertically in the grooves C. The levers are shouldered at their extremities, the extremities setting respectively in the recesses in the bolster and the box or beam supporting the carriage-seat.

The letter G indicates a series of spiral springs, which are located in the above mentioned recess. The shouldered ends of the levers rest in the ends of these springs, as shown in Fig. 1 of the drawings. The levers are adapted to play in the recesses in the bolster and body-supporting box or beam, as will be evident from the drawings, permitting the body to ride easily and freely.

Although I have described my invention as particularly applicable to vehicles, it is evident that it may be employed with equal advantage in all cases where such springs are used—for instance, for buggy-seats, car-seats, and the like.

Having thus described my invention, what I claim, and desire to secure by Letters Patent, is—

The combination, with the recessed bolster and body-supporting box or recessed bar, of the levers, pivoted together by a fulcrum-pin, adapted to play in vertical guide-grooves, and the springs fitted in the respective recesses and to the shouldered ends of the levers, substantially as specified.

In testimony whereof I affix my signature, in presence of two witnesses, this 5th day of May, 1882.

NELSON B. COOPER.
